UNITED STATES PATENT OFFICE.

GEORGE PETER, OF ROCHESTER, NEW YORK.

JOINTER-GUARD.

1,111,671.

Specification of Letters Patent. Patented Sept. 22, 1914.

Application filed May 22, 1914. Serial No. 840,319.

To all whom it may concern:

Be it known that I, GEORGE PETER, a citizen of the United States, residing at Rochester, in the county of Monroe and State of New York, have invented new and useful Improvements in Jointer-Guards, of which the following is a specification.

The general object of this invention is to effect the protection of the knives or cutting elements in surfacing machines, and the like, whereby an operator may be shielded therefrom while operating the same.

Another object is the provision of a guard or shell for the cutting-elements of surfacing-machines or the like, which may be adapted for adjustment, so that the knives may be guarded at all times, notwithstanding the position of the work on the machine. And to these ends the invention consists of an adjustable guard plate arranged on the upper face of the machine adjacent to the cutting-elements thereof, and means for connecting the guard to the machine so that the same may be effectively operated.

Other objects will appear and be better understood from that embodiment of my invention of which the following is a specification reference being had to the accompanying drawings forming part hereof, in which;

Figure 1 is a side elevational view of a machine showing my invention applied thereto. Fig. 2 is a detail top plan view of a portion of Fig. 1 showing the guard plate in position thereon. Fig. 3 is a detail elevational view of the guard having a portion broken away for the purpose of clearness, and Fig. 4 is a horizontal cross sectional view taken on the line 4-4 in Fig. 3.

As shown in the drawings *a* indicates a surfacing machine of usual construction, which is provided with the work table *b* and the guide *c*, and *d* indicates my improved jointer guard which comprises the guard plate *5*, mounted in the upright shaft *6*, which is journaled in the brackets *7* and *8* mounted on the side of the machine as shown in Fig. 1.

The guard plate may be made of any suitable material such as wood or the like and is preferably formed of the shape shown in the drawings, having an arcual portion *5'* whereby the guard may be always in contact with the guide *c* or the work placed thereagainst, and thus admits of the guard

plate covering the knives (not shown) when in any adjusted position. For the purpose of mounting the guard plate on the shaft *6*, the plate is provided with a sleeve *9*, which has a flange *10* on its upper end, whereby the plate is secured to the sleeve by screws or other suitable means, and for the purpose of detachably securing the sleeve on the shaft *6*, the sleeve is provided with a set screw *11* which is adapted to engage with the end of the shaft as shown. The brackets *7* and *8* which support the shaft are secured to the machine, at any suitable portion thereof, such as at the side, as shown in the drawings, by means of the bolts *7'* and *8'* or the like.

The bracket *8*, as will be seen, is provided with an enlarged bearing portion which provides a suitable housing *12* and for the purpose of providing access to the interior of the housing a bored top-plate *13* is detachably secured thereto by means of screws or the like as shown. This bracket *8* forms a bearing for the lower end of the shaft *6* and arranged within the housing is a sheave *14*. This sheave is disposed horizontally in the housing and is provided for the purpose of receiving a flexible element *15*; the housing is also provided with a second sheave *16* which is located at the rear portion of the housing and is disposed vertically therein so as to rotate in a plane which is tangent to the periphery of the sheave *14*. A flexible element shown in the form of a chain *15* is wound around the sheave *14* which functions as a drum therefor, and is trained over the smaller sheave *16* whence it depends; and as shown in the drawings the free end of this chain is provided with a weighted element *17* which is preferably of sufficient weight so as to facilitate the rotation of the shaft *6* for the purpose of normally holding the guard plate in contact with the guide *c*.

Now, it will be seen that upon work being placed upon the table of the machine, the guard plate *5* may be normally controlled and may be swung in contact therewith so that the knives (not shown) are covered and thus protected from injuring the operator's hands or other parts of the body, and by virtue of counter-action of the weight the guard plate will remain in a relatively fixed adjusted position, and remain so until re-adjusted as stated.

It will also be noted by referring to Figs. 1 and 3 that by virtue of the bearing *9* and

the set screw 11 the guard plate 5 may be adjusted vertically, and thus the guard plate may be regulated in conjunction with the adjustment of the working-table 3, should 5 the adjustment of the latter be desired, during the operation of the machine.

It is obvious that those skilled in the art may vary the details of construction and arrangements of parts without departing 10 from the spirit of my invention and therefore I do not wish to be limited to any such features except as may be required by the claims.

What I claim as new is:—

- 15 1. A guard of the class described comprising a pair of brackets adapted to be secured to a machine or the like, one of said brackets having a housing formed therein, a drum located within the housing, and 20 adapted to rotate horizontally therein, a vertical sheave disposed tangentially to the drum and pivoted in the housing, a flexible element wound around the drum and trained over the sheave so as to have its end depend 25 therefrom, a weight carried by the end of the flexible element, a vertical shaft carried by the drum and journaled in the brackets and a guard plate detachably secured to the

upper end of the shaft substantially as described.

2. A guard of the class described comprising a pair of brackets adapted to be secured to a machine or the like, one of said brackets having formed therein an enlarged housing, 30 a detachable cover for the housing provided with a central opening, a drum located within the housing and adapted to rotate horizontally therein, a vertical sheave pivoted in the housing and disposed tangentially to the periphery of the drum, a vertical shaft 35 securely mounted on the drum and journaled in the brackets, a guard plate detachably mounted on the upper end of the shaft and adapted to have vertical adjustment thereon, a flexible element wound around the drum 40 and trained over the sheave so as to depend from the housing, and a weight carried by the depending end portion of the element 45 for the purposes set forth.

In testimony whereof I affix my signature 50 in presence of two witnesses.

GEORGE PETER.
